Primary Examiner — T. Chase Nelson*Assistant Examiner* — Jonathan J Han(74) *Attorney, Agent, or Firm* — Guice Patents PLLC(57) **CLAIM**

The ornamental design for an angled fore grip, as shown and described.

DESCRIPTION

FIG. 1 is a perspective view of an angled fore grip showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view showing an angled fore grip from another position; and,

FIG. 9 is a view showing the application thereof, wherein the broken lines in the drawing are used to illustrate unclaimed environmental structure and form no part of the claimed design.

The ornamental design which is claimed is shown in solid lines in the drawings.

1 Claim, 8 Drawing Sheets(56)
